VACUUM TUBE AMPLIFIER

Jabez C. Street, Belmont, Mass., assignor, by
mesne assignments, to the United States of
America, as represented by the Secretary of the
Navy

Application October 4, 1943, Serial No. 504,924

6 Claims. (Cl. 250—27)

1

This invention relates to vacuum tube amplifiers and particularly to high frequency amplifiers having a wide range.

One of the objects of the invention is to provide a wide band, high frequency amplifier with two or more stages of amplification in which all of the tubes are on at the same time and off at the same time.

Another object of the invention is to provide a high frequency, wide band amplifier of the above type in which high amplification may be obtained.

Another object of the invention is to produce amplification at high voltage and high power levels with great efficiency.

Another object of the invention is to provide a circuit for a thermionic tube in which the potential of the cathode is caused to vary with the plate-cathode current of the tube without altering the grid-cathode potential difference.

A more specific object of the invention is to provide an amplifier consisting of two or more stages in which the input of one stage is obtained from the cathode circuit of the previous stage in such a way that high amplification is realized.

Still another object of the invention is to provide a complete pulse-forming and amplifying circuit for producing discrete pulses spaced at predetermined time intervals at unusually high efficiencies.

Other objects and objects relating to the manner of arranging and connecting the various parts of the circuit will be apparent as the description of the invention proceeds.

The invention is illustrated in the accompanying drawings in which:

Fig. 1 is a circuit diagram of a transmitter and associated pulse-forming and driving circuit incorporating the invention and arranged to cause the transmitter to transmit a succession of timed discrete pulses of high frequency oscillations;

Fig. 2 is a circuit diagram of a modified form of the circuit of Fig. 1; and

Fig. 3 is a circuit diagram of another modification of the invention in which a plurality of stages are used for greater power output.

In conventional forms of resistance-capacity coupled amplifiers each stage reverses the polarity of the signal from the stage before it. Where it is desired to amplify a single pulse, if the first tube of such an amplifier were arranged to conduct when the pulse was transmitted, then the second tube would be shut off during that

2

period, the third tube would conduct, the fourth tube would be shut off, and so on. At the end of the pulse the first tube would shut off, the second tube would then conduct, the third tube would shut off, the fourth tube would conduct, and so on. This means that when no pulse is being transmitted, alternate tubes are conducting and consuming plate circuit power. Where discrete pulses are being transmitted which are separated from each other a greater time duration than the duration of one pulse, half of the tubes are on during the period when no pulse is transmitted, and since this time is greater than the period of the pulse, a great deal of energy may be consumed without producing a beneficial result. The amplifier of the present invention provides that all of the tubes are shut off when no pulse is being transmitted and all are on when a pulse is being transmitted, and this is done without loss of amplification.

In general, the invention comprises, as a principal feature, an amplifier in which a tube is provided with a resistance in its cathode circuit and the output of the tube is taken from across this resistance, as it is in a cathode follower circuit, but, unlike the cathode follower circuit, the grid of the tube is caused to rise and fall as the potential across the resistance rises and falls without affecting the potential difference between the grid and cathode of the tube caused by a signal applied to the grid.

In the circuit shown in Fig. 1, a gas tube 10 and associated circuit delivers a positive square pulse of a predetermined time duration to the grid circuits of three tubes 11, 12, and 13 which are connected in parallel. This pulse is amplified in the tubes 11, 12, and 13 and delivered, still as a positive pulse, to the grids of two amplifier tubes 14 and 15, arranged in parallel. These tubes reverse the polarity of the pulse and drive a transmitting oscillator tube 16 which is so arranged and connected in the circuit that it will transmit only during the period of the negative pulse. Tubes 10 to 16 inclusive are either all on or all off at a given time.

The tube 10 may be of the type in which the grid has control of the tube only when the tube is not conducting. As shown, this tube has a plate 19, a control grid 20, and a cathode 21 which is heated by a heater 22, the latter being energized by a source of alternating current from the secondary of the transformer 23 which is shown under the tube 13. The letters X—X indicate the heater connection the circuit of which has been omitted to avoid confusion.

A positive trigger pulse, indicated at 25, from some suitable pulse-forming circuit (not shown), is fed to the grid 20 through a condenser 26 and a relatively high resistance 27 which is provided for a purpose to be hereinafter explained. The plate 19 has connected to it a network 28 which may comprise a plurality of π sections of inductances 29 and condensers 30. The inductances 29 may be equal in value. The condensers 30 also may be equal in value with the exception of the end condensers which may have a value of one half the capacity of the others. One end of the series inductances of this network 28 is connected to the plate 19 of the tube 10 and this same end, or any point along the series inductances, is connected through a relatively high resistance 31 to a positive source of potential which will be described later. The common junction of the condensers in the network 28 is connected through a cathode resistance 32 to the cathode 21 of the tube 10. The value of the resistance 31 should be such that, taken in connection with the conductances of the input circuit of the tubes 11, 12, and 13, the impedance of the circuit across the network 28 will be substantially equal to the characteristic or surge impedance of the network 28.

When the tube 10 is non-conducting, the condensers in the network 28 charge through the resistance 31 and through the remainder of the cathode circuit, which will be subsequently described. When a positive trigger pulse, as, for instance, the pulse 25, is applied to the grid of the tube 10, the tube becomes conductive and the condensers 30 start to discharge through it and through the resistance 32. The effect of the inductances 29 and condensers 30 in the network 28 is to cause a potential to appear across the resistance 32 which is equal to one half of the voltage to which the condensers 30 were charged. A voltage wave-front then travels towards the right to the open end of the network and is reflected back toward the plate 19 and resistance 32. During the time this wave is traveling, the voltage across the resistance 32 remains at the same value, but when the wave reaches the plate 19 and resistance 32 again, the voltage across the resistance 32 is reduced to zero, which causes the tube 10 to shut off and be placed under control of its grid 20 again. Thus, a positive square pulse of a time duration determined by the component parts of the network 28 is produced across the resistance 32. Such a pulse-forming network is shown and described in the application of J. C. Street, Serial No. 479,660, filed March 18, 1943. Other pulse-forming networks which may be used are shown and described in the application of Ernst A. Guillemin, Serial No. 492,160, filed July 6, 1943. The pulse forming circuits disclosed in the latter reference are also of the lumped constant type, the elements being so arranged such that a uniform transmission line is simulated. A source of charging voltage is connected to the artificial line, and a switch tube is provided to initiate the charging and discharge of the line.

The cathode 21 of the tube 10 is connected through a large coupling condenser 33 and a resistance 34 to a common conductor 35 for the grid circuits of the tubes 11, 12, and 13. These tubes, in the particular arrangement shown, are beam power amplifier tubes and the grids 36, 37, and 38 of the tubes 11, 12, and 13, respectively, are connected respectively through small grid re-

sistances 39, 40, and 41, for suppressing parasitic oscillations to the common grid connection 35. The cathodes 42, 43, and 44 of the tubes 11, 12, and 13 are connected together and to the end of the cathode resistance 32 which is not connected to the cathode 21 of the tube 10. It will thus be seen that the cathode resistance 32 is connected between the grids of the tubes 11, 12, and 13 and the cathodes of those tubes, and hence the positive pulse which appears as an increase in the potential difference across this resistance 32 will also appear as an increase in the potential difference between the grids and cathodes of the tubes 11, 12, and 13.

The cathodes 42, 43, and 44 of the tubes 11, 12, and 13 are further connected through a common cathode resistance 48 to a constant potential point 47 on the power supply which will be described later, and through a resistance 49, which is a part of the power supply circuit, to ground, as indicated at 50. These cathodes are heated by heaters 52, 53, and 54 which are electrically connected to the cathodes and which derive energy from the secondary of the transformer 23, as indicated by the letters X—X, the wiring for the heaters of the tubes 11 and 12 having been omitted to avoid confusion.

The cathodes of the tubes 11, 12, and 13 are also connected through grid resistances 56 and 57 to the grids 58 and 59 of the tubes 14 and 15, respectively. These amplifier tubes may be of the type having filamentary cathodes 60 and 61, respectively, which are energized from the secondary of a transformer 62, the connections being indicated by the letters Y—Y. The midpoint of each of these filaments is connected through a common resistance 63 to ground, as shown.

It will be seen that the grid circuits of the tubes 14 and 15 are connected across the cathode resistance 48 which appears in the circuit which is common to the cathodes of the tubes 11, 12, and 13, and hence any difference in potential which is produced across this resistance will also appear between the cathode and grid of each of the tubes 14 and 15.

The positive pulse appearing on the grids of the tubes 11, 12, and 13 will cause these tubes to conduct during the pulse which will produce a certain potential difference for the period of the pulse across the resistance 48 and thus produce a positive pulse upon the grids of the tubes 14 and 15, causing these tubes also to conduct during the time of the pulse. The plates 66 and 67 of the tubes 14 and 15 are supplied with a positive potential through low resistances 68 and 69, respectively, which are used to suppress parasitic oscillations, since the tubes are in parallel, and through the common load resistance 70 from a source of potential to be described later.

The tube 16 may be a high-frequency oscillator, as, for instance, a magnetron, and the plates of the tubes 14 and 15 may be connected respectively through the resistances 68 and 69 and a condenser 73 to the cathode 72 of the tube 16. The tube 16 has one side of its heater 74 connected to the cathode 72, and the heater is energized from the secondary of a suitable transformer 75, the primary of which is well insulated from the secondary and is connected to a source of alternating current. The plate 78 of the tube 16 is connected to ground, as shown, and a bleeder resistance 79, in parallel with an inductance 80, is connected between the cathode 72 and the plate

78. The high-frequency energy is led off by means of the pick-up loop 81 and coaxial line 82.

The tube 16 is operated preferably with its anode connected to ground, as shown, because this type of tube is usually made with the anode forming part of the metallic shell of the tube. Hence it would be difficult to insulate the anode from ground and to eliminate the effect of the large capacity between the shell of the tube and ground.

The condenser 73 is normally charged, and when the tubes 14 and 15 become conductive during the period of the pulse, the condenser 73 discharges through the tubes 14 and 15 and through the tube 16, thus causing the tube 16 to oscillate. The potential across the condenser 73 when charged may be in the order of ten thousand volts or more.

There is some distributed capacity to ground in the cathode of the magnetron tube 16 and in the wiring connected to the cathode. This capacity tends to charge during the pulse and to discharge across the magnetron tube at the end of the pulse, with the result that instead of a sharp cut-off of the pulse, the end of the pulse is caused to trail off as the capacity discharges. This capacity has been illustrated by the condenser 83, shown in dotted lines from the cathode to the plate of the magnetron tube. The inductance 80 is provided to help discharge this capacity at the end of the pulse. When the value of the inductance 80 is properly chosen, the end of the pulse will produce a voltage surge which will be applied across the capacitance 83 in the opposite sense to the charge thereon, causing the capacitance to discharge quickly. In order to prevent an oscillation being set up in the circuit of the inductance 80 and stray capacitance 83, the resistance 79 is provided to damp out this circuit. In place of the resistance 79 a diode thermionic tube may be used with the plate connected to the cathode of the magnetron and the cathode of the diode tube connected to the plate of the magnetron.

In order to produce the plate voltages for the tubes 10 to 13 inclusive and the grid biases for these tubes I utilize two half-wave rectifier tubes 85 and 86. These tubes are arranged so that the tube 86 will produce several hundred volts above ground for the plates of the tubes 11, 12, and 13, while the tube 85 will produce over a thousand volts below ground for the cathode voltages of the tubes 10, 11, 12, and 13, and the grid bias voltages of these tubes and the tubes 14 and 15. To this end the filaments 87 and 88 of the rectifier tubes 85 and 86 are connected to separate filament windings 89 and 90, respectively, on a transformer 91, the primary 92 of which is energized from a suitable source of alternating current. A high voltage winding 93 has one end connected to the filament winding 89 and the other end connected to a terminal 94 which forms one end of a parallel voltage divider circuit, one branch of which includes a resistance 95, the resistance 49, already mentioned, and a resistance 96, connected in series in the order named to a terminal 97 connected to the plate 98 of the rectifier tube 85. The other branch of the voltage divider circuit comprises resistances 99 and 100, connected in series between the terminals 94 and 97 in the order named. A filter condenser 101 is connected between the terminals 94 and 97, a filter condenser 102 is connected across the resistance 96, and a filter condenser 103 is connected across the resistance 100. The potential appearing between 75 the resistances 98 and 51 through a resistance

the terminals 94 and 97 may be in the order of 1200 volts with the terminal 97 negative and the terminal 94 positive.

The rectifier tube 86 is connected in series with 5 a portion of the secondary winding 93 of the transformer 91, the plate of the tube being connected to an intermediate point 104 on the secondary winding. A condenser 105 is connected between the terminal 94 and a terminal 106 which 10 is connected to the filament of the rectifier tube 86. The voltage developed between the terminals 94 and 106 may be in the order of 500 volts with the terminal 106 being positive.

The grid 20 of the gas tube 10 is biased by connecting it through a grid resistance 117 to the negative terminal 97 on the power supply, and the common grid connector 35 for the tubes 11, 12, and 13 is also connected to this terminal through a grid resistance 118. The screen grids 123, 124, and 125 of the tubes 11, 12, and 13, respectively, are connected to a terminal 107 on the power supply, which is at the juncture of the resistances 99 and 100, through a screen grid resistance 126, a by-pass condenser 127 being connected between the screen grids and the cathodes. The plates 130, 131, and 132 of the tubes 11, 12, and 13 are connected respectively through parasitic oscillation suppressor resistances 133, 134, and 135 to a common plate connection 136 which 30 is connected directly to the positive potential terminal 106.

The network 28 in the plate circuit of the tube 10 receives its positive potential through the resistor 31, which is connected between the network and the terminal 107 which point may be several hundred volts more positive than the terminal 47. The resistance 31 is made sufficiently large so that there will not be enough voltage difference between the plate and cathode of the tube 10 to keep the tube conducting after the pulse has been formed, but this resistance is not so large as to prevent the condensers 30 in the network 28 from charging sufficiently during the time between pulses.

45 The plate supply for the two tubes 14 and 15 is furnished by four half-wave rectifier tubes 138, 139, 140, and 141, arranged in a bridge circuit. The filaments of these tubes and the high voltage is supplied from two separate transformers 142 50 and 143, respectively, so as to be able to control the high voltage independently of the filaments, and the output of this power system is connected across a bleeder resistance 144. The negative end of this resistance 144 is grounded, as at 145, 55 and the load resistor 70 is connected between the positive end 146 and the juncture of the resistances 68 and 69 in the plate circuits of the tubes 14 and 15.

The stray capacities to ground of the input circuit of the tubes 14 and 15 and the grid-cathode 60 capacitances of these tubes may tend to prevent the rapid drop of the potential of the grids of these tubes at the ends of the pulses. In order to discharge these stray capacities at the end of each pulse to give a short cut-off, a gas tube 150 may be provided with its plate 151 connected to the grid circuit of the tubes 14 and 15 through a resistance 152, and the filamentary cathode 153 connected to the terminal 47 on the power supply through a cathode resistance 154. A condenser 155 is connected across the resistance 154 and a condenser 156 is connected between the grid 149 and the cathode. In addition, the grid is connected to the juncture of the resistance 152 and 65 the resistances 56 and 57 through a resistance

157 and also to the terminal 41 through a resistance 158. The filament 153 is energized from a secondary winding 159 on the transformer 91, as indicated by the letters Z-Z which appear at both places on the diagram, the wiring having been omitted to avoid confusion.

Assuming that the tube 150 is non-conducting when the pulse appears across the resistance 48, it will be seen that the grid 149 will assume some potential intermediate of the total pulse potential because of the voltage-divider action of the circuit connected to the grid. The values of resistances 157, 154, and the condenser 156 are made such that the voltage of the grid 149 will rise as the condenser 156 is charged, but will not become sufficiently positive with respect to the cathode 153 to fire the tube until the time duration of the pulse has elapsed. At this time the tube fires and forms an instantaneous discharge path for the grid circuits of the tubes 14 and 15 through the resistance 152, which is made relatively small, the plate-cathode circuit of the tube 150, the condenser 155, to the terminal 41 on the power supply. The condenser 155 is charged while the tube 150 is conducting, because of the potential drop across the resistance 154, which is given a high value, and this charge on the condenser 155 biases the tube by maintaining the cathode 153 more positive than the grid 149, or at least as positive as the grid, during the period between pulses. The resistance 154 is made sufficiently large to prevent the condenser 155 discharging too much during this period. Because of the action of the tube 150 and associated circuit, the grids of the tubes 14 and 15 discharge immediately at the end of the pulse, causing the tubes 14 and 15 to cut off at this time.

It is desirable to drive the gas tube 10 with a higher input voltage than the characteristics of this tube would normally require, so as to provide greater accuracy in the firing of the tube. When a high voltage trigger pulse is applied to the grid of the gas tube 10, the potential of the grid will reach the firing point in quicker time than when a low voltage pulse is applied, and this time will be more constant for successive trigger pulses than where a low voltage trigger pulse is used. In order to drive the tube 10, I have shown in Fig. 1 a two-stage voltage amplifier comprising the triode tubes 160 and 161, these tubes deriving their plate potential from the positive potential terminal 106 along with the plates of the tubes 11, 12, and 13. These tubes 160 and 161 are shown coupled together and to the gas tube 10 with resistance-capacity coupling in a conventional manner. An advantage of using two tubes for this purpose is that the first tube may be driven with a positive trigger pulse, which permits the tube to be biased sufficiently past cut-off so that any hum picked up in the line from the trigger-producing circuit may be eliminated. Of course, the trigger pulse should be long enough to permit the capacity of the grid circuit of the tube 10 to acquire voltage.

In the operation of the circuit of Fig. 1, a positive trigger pulse is applied to the grid 20 of the tube 10 through the amplifier tubes 160 and 161 and swings the grid of the tube 10 above the critical conducting potential with respect to its cathode, whereupon the tube 10 becomes conductive. The capacities 30 in the network 28 which had been fully charged by the difference in potential between the terminals 107 and 47 in the power supply circuit, start to discharge through the tube 10 and the resistance 32, and

a sudden increase in potential difference for the duration of the resulting positive square pulse is produced across the resistance 32, as has already been described.

Since the resistance 32 is connected between the grids and cathodes of the tubes 11, 12, and 13, the positive square pulse appears between these grids and cathodes. The tubes 11, 12, and 13, therefore, immediately increase in conductivity and a square pulse of plate-cathode current flows through the tubes and therefore through the cathode resistance 48. This current causes a sudden increase in potential difference to develop across the resistance 48 and causes the cathodes of the tubes 11, 12, and 13 to become more positive in potential than the terminal 47 on the power supply for the duration of the pulse, but, since the cathode 21 of the tube 10 is connected to the cathodes of the tubes 11, 12, and 13, this cathode rises up in potential with the cathodes of the tubes 11, 12, and 13. Because the cathode 21 of the tube 10 is coupled to the control grids of the tubes 11, 12, and 13 through the coupling condenser 33, these grids will also ride up in potential and the difference in potential between the grids and the cathodes of these tubes caused by the pulse will be maintained.

A strong positive pulse is therefore formed across the resistor 48 which pulse is then applied to the grids of the tubes 14 and 15, the gas tube 159 acting to reduce the potential on these grids quickly at the end of the pulse, as has already been described. The tubes 14 and 15 become conductive during this pulse and act as a switch to discharge the condenser 73 through the oscillator tube 16. This causes the oscillator tube to operate and produce high-frequency oscillations during the period of the pulse, the inductance 80 together with the resistance 79 acting to damp oscillations which might occur at the end of the pulse, as previously described. The tubes 14 and 15 are biased far enough below cut-off to hold off the high plate voltages before the pulse, and the potentials on the grids must rise very quickly to a very high value to cause the tubes to conduct immediately and freely.

Referring again to the operation of the gas tube 10, it has been stated that the potential of the cathode 21 rises up with the potential of the cathodes of the tubes 11, 12, and 13, and that, because of the coupling through the condenser 33, the grids of the tubes 11, 12, and 13 also ride up in potential during the pulse. However, since there is a circuit between these grids and the grid 20 of the tube 10 through the resistances 118, 117, and 21, the grid 20 of the tube 10 will also ride up in potential. The resistance 21 is therefore made sufficiently high in order to prevent the positive pulse which thus appears on the grid 20 of the tube 10 from causing an instantaneous surge of grid current to ground through the tube 161, which is in the input circuit of the tube 10, or through the plate resistor of the tube 161.

The resistances 117 and 118 act as grid-leak resistances for the tubes 10 and the parallel tubes 11, 12, and 13. The resistance 32 is made as large as feasible, so that when the resistance 34 is placed in the parallel resistance circuit, previously described, maximum signal will appear at the grids of the tubes 11, 12, and 13.

The cathode resistances 32 and 48 are connected in series through the resistance 96 of the power supply and the above described resistances 117 and 21 in the grid circuit of the tube 10, and

hence the drop in potential across the resistances 32 and 48 appears between the grid 20 and cathode 21 of the tube 10 during the pulse. Since the tube 10 is conductive during the pulse, the resistances 27 and 117 also perform the important function of preventing the shorting of the pulse between the grid and cathode of the tube 10.

It will be seen that all of tubes 10 to 16 inclusive in the pulse-forming and amplifying circuit of Fig. 1 are on during the period of the pulse and are off between pulses. It will also be seen that, since the potential of the grids of the tubes 11, 12, and 13 rises with the cathodes of those tubes, the signal causes no decrease of the potential of the grids with respect to the cathodes. Thus, in addition to the tubes all being on during the pulse, the circuit still amplifies and a high gain may be obtained from it. The amplifier of the invention therefore, becomes especially useful where discrete pulses, spaced at predetermined time intervals, are produced, and economy of operation can be obtained with great amplification.

Where the circuit of the invention is used, as is shown in Fig. 1, to operate a high-power output device, such as the magnetron 16, the parallel tubes 11, 12, and 13 must normally have a large negative potential on their grids and these grids must quickly rise in potential during the pulse to a large positive potential. A conventional amplifier would not fulfill this requirement unless an extremely high amplitude square driving pulse were available to apply to the grid of the amplifier. This pulse might be in the order of 1200 volts positive. In the circuit of the invention both the cathodes and grids of the tubes 11, 12, and 13 are negative by a large amount, there being just enough difference in potential between the cathodes and grids to keep the tubes normally cut off. A positive pulse in the order of about 250 volts applied to the grids of these tubes will raise their potential far enough above the potential of the cathodes to cause the tubes to conduct, thus raising the potential of the cathodes towards the potential of the plates. By back-coupling from the cathodes to the grids of the tubes through the large coupling condenser 33, which presents negligible reactance to all frequency components in the repeating pulse spectrum, the grids rise in potential with the cathodes but maintain the potential separation between them and the cathodes during the pulse by the magnitude of the original pulse applied therebetween. All of this is done with great efficiency.

The gas tube acts, in the illustration shown, as a switch which is capable of being operated by a trigger voltage pulse and which is used in the circuit because of its functional part in the pulse-forming operation.

It may be seen that the change in potential at the cathodes of tubes 11, 12, and 13 with the pulse is equal to the arithmetical sum of the potentials of points 47 and 106 less the voltage drop in one of the tubes 11, 12, or 13 and in its corresponding plate resistor 133, 134, 65 or 135.

It may be further noted that the resistor 48 isolates a preceding portion of the circuit consisting principally of tubes 10, 11, 12, and 13 and their associated circuit components, from the potential of point 47 as a result of the voltage drop in the resistor 48 during the pulse. This portion of the circuit is therefore raised in potential during the pulse.

In Fig. 2 I have shown a modified form of the 75

invention, although operating on the same general principles. In this circuit a gas tube 162, which may be similar to the gas tube 10 of Fig. 1, has its grid 163 connected through a resistance

5 164 to the cathode 165 of a diode tube 166. The trigger pulse is delivered to the plate 167 of this diode tube. The cathode 165 of this tube is connected through resistances 168 and 169 to a source of negative bias potential, indicated at 10 170. This provides the bias for the grid 163 of the tube 162. The plate 167 of the diode tube 166 is also connected through a resistance 171 to the source of negative potential 170. Thus connected, a positive pulse received on the plate 15 167 of the diode tube 166 may pass through the tube because of the rectifying action thereof and will appear directly on the grid 163. However, a positive pulse produced on the grid 163 by the action of the circuit following the tube 162 can 20 not pass through the tube 166 to affect the trigger-pulse-producing circuit. The diode 166, therefore, performs the function of a buffer circuit. Grid current in tube 162 is limited to allowable values by the resistances 164, 168, 25 and 169.

The gas tube 162 has a cathode 172 which is connected directly to the grid 173 of a driver tube 174. The heater 175 for the cathode 172, which is shown connected to the cathode, may 30 be energized from the secondary of a suitable transformer 176, the primary of which is connected to a source of alternating current. The cathode 172 is also connected through a condenser 177 to the juncture of resistances 168 and 35 169 in the grid circuit of the tube 162.

In order to bias the grid 173 of the tube 174, this grid is connected to a source of negative bias potential, indicated at 178, through an inductance 179, a resistance 180, and another resistance 181, arranged in series in the order named.

The plate 182 of the tube 162 is given a positive potential through a resistance 183 from a source of potential indicated at 184. A condenser 185 is connected between the plate 182 of the tube 162 and the juncture of resistances 180 and 181.

The tube 174 is shown as a screen grid tube having a filamentary cathode 186 which is energized from the secondary of a transformer 50 187 whose primary is energized from a suitable source of alternating current. The cathode 186 is connected by means of a condenser 188 to the juncture of the resistances 180 and 181, and the cathode is also connected through an inductance 189 to ground.

The plate 190 of the tube 174 is connected through a plate resistance 191 to a source of positive potential, indicated at 192, the plate being also connected through a by-pass condenser 193 to ground. The screen grid 194 of this tube is connected through a screen resistance 195 to a source of positive potential, indicated at 196, the screen grid being also connected to the cathode through a by-pass condenser 197. The output of this circuit is through a condenser 198 which is connected to the cathode 186 of the tube 174.

In the operation of this circuit the tube 162 is normally non-conducting. Under such a condition the condenser 185 is charged since it is connected in series with the resistance 183 and the resistance 181 across the positive and negative potential sources 184 and 178. A positive pulse is now delivered to the plate 167 of the

diode tube 166 from a suitable circuit which produces the trigger pulse. This positive pulse passes through the plate-cathode circuit of the diode tube 166 and is impressed upon the grid 163 of the gas tube 162. This grid is thus swung in the positive direction with respect to the cathode 172 above the critical potential and the tube becomes conductive, thus taking the control away from the grid.

As soon as the tube 162 starts to conduct, the condenser 185 discharges through the tube and through the inductance 179 and resistance 180. The grid 173 of the tube 174 was at the potential of the negative source 178, but immediately swings in the positive direction because of the voltage now applied across the inductance 179 and the resistance 180. The values of the inductance 179 and resistance 180 are chosen so that the action of the condenser 185 in discharging through this circuit will produce in effect a positive pulse with steep leading and trailing edges on the grid 173 of the tube 174, causing it to draw grid current.

The positive pulse on the grid of the tube 174 causes this tube to conduct and the plate-cathode current will flow through the inductance 189. The sudden surge of current through the inductance 189 will raise the potential of the cathode 186, and, since this cathode is coupled through the condenser 188 to the grid 173 of the tube 174, this grid will also be raised in potential a corresponding amount, thus maintaining, during the period of the pulse, the potential difference between the grid and cathode of the tube 174 which was originally produced by the action in the plate-cathode circuit of the tube 162.

The cathode 172 of the tube 162 also rises with the grid 173 and produces a rise in potential of the grid 163 by virtue of the coupling through the condenser 177. This prevents the grid 163 of the gas tube from becoming so negative with respect to the cathode as to affect the conductivity of the tube before the pulse has been completed.

The inductance 189 may be used in the cathode circuit of the driver tube only when it presents a high reactance to the frequency components of the signals used to operate the circuit. When this condition is satisfied, the inductance will push the cathode up in potential with the signal variations.

In the circuit of Fig. 2 it will be seen that the tubes 162 and 174 are both on during the pulse and off between pulses, and it will be seen also that the output may be taken from the cathode of the tube 174 with no sacrifice of gain.

In some instances where greater power is desired additional stages of the circuit of the invention may be used. In such a case all stages except the last are caused to rise and fall in potential with the potential of the cathode of the amplifier tube in the last stage. The circuit of Fig. 3 illustrates such an arrangement. In this circuit the trigger pulse passes through a diode tube 200 and is applied to the grid of a gas tube 201. The plate circuit of the tube 201 is provided with a network 202, similar to that shown in Fig. 1, for producing a square pulse when the tube 201 is made conducting, which pulse may be adjusted in time duration by switching in or out sections of the network. This network is connected across the tube 201 and a resistance 203 which is in the cathode circuit thereof. The resistance 203 is also connected in the input cir-

cuit of a screen grid tube 204, the cathode of the tube 201 being connected through a coupling condenser 205 to the grids of the tube 204 through parallel resistances 206 and 207, while the other end of the resistance 203 is connected directly to the cathode of the tube 204. A resistance 208 is provided in the cathode circuit of the tube 204, across which resistance the output of the first stage is taken.

10 The gas tube 201 and the tube 204 are connected similarly to the circuit of Fig. 1, the potential of the gas tube 201 being free to rise and fall as the potential difference across the resistance 208 varies. I have found it desirable to enclose the tubes 200, 201, and 204 and also the network 202 and associated circuits within a metal container 210 which forms an electrostatic shield for these components and a convenient auxiliary ground which is isolated from the main ground connection. The various leads for supplying potentials to the circuit are filtered with resistances and condensers as they pass through openings in the container 210. The cathode of the tube 204 is connected through the resistance 208 to the container, as shown at 211.

In the arrangement shown the container 210 is now arranged to follow the potential of the cathodes of another stage of amplification. This other stage may comprise two twin amplifier tubes 212 and 213 connected in parallel, with the cathodes thereof connected together and to ground through a resistance 214 shunted by a choke 215. The container 210 is connected by means of the wire 216 to the cathodes of the tubes 212 and 213, while the cathode of the tube 204 is connected through a coupling condenser 217 to the grids of the tubes 212 and 213 through parallel resistors 218 and 219; for the tube 212, and 220 and 221, for the tube 213.

40 The separate circuit associated with the tubes 212 and 213, together with the container 210, is then enclosed in a container 224, the container 224 being connected to ground and all of the leads for both circuits being filtered with resistances and condensers as they pass through openings in the container 224. The output of the circuit is obtained from the cathodes of the tubes 212 and 213 through a condenser 225, the output being indicated at 226.

50 The purpose of the double shielding arrangement of Fig. 3 is to prevent any tendency to oscillate which may be caused by the screen grids of the tube 204 being connected together within the tube and which may be enhanced by the additional isolated components of the circuit.

An impedance in the input circuit of the diode 200 is desirable to prevent large interaction of the pulse upon the trigger-producing circuit, since the voltage of the pulse is high, but a sufficiently high impedance for the purpose reduces the signal applied to the grid of the tube 201. I therefore provide an inductance 228 in series with the plate of the diode tube 200 and shunt this inductance with a resistance 229 to damp out oscillations. The inductance offers low impedance to the frequency components of the trigger pulse but high impedance to the higher frequency components of the square pulse produced by the tube 201 and associated circuit, thus adding to the effect of the diode tube 200 to isolate the tube 201 from the pulse-producing circuit.

In the operation of this circuit a positive trigger pulse delivered to the diode tube 200 will swing the potential of the grid of the tube 201 in the positive direction, so as to start this tube

conducting with negligible voltage drop. This will connect the network 202 across the resistance 203 which will cause a potential drop to appear across this resistance for a period of time determined by the network 202. The potential across the resistance 203 is applied between the grids and the cathodes of the tube 204 so as to cause this twin tube to conduct during the period of the pulse. The flow of current through the tube 204 produces a potential drop across the resistance 208 in the cathode circuit thereof, and this potential difference is applied between the cathodes and grids of the tubes 212 and 213 which are thus caused to conduct during the period of the pulse. Current flowing in the tubes 212 and 213 causes a potential drop across the resistance-choke combination 214 and 215, between the cathodes of the tubes 212 and 213 and ground. Since the resistance 214 and choke 215 are in the cathode circuit of the tubes 212 and 213, the cathodes of these tubes will rise in potential with respect to ground in proportion to the current flowing in these tubes. But the container 210 is connected to the cathodes of the tubes 212 and 213 and therefore also rises in potential during the period of the pulse. The resistance 208 connected in the cathode circuit of the tube 204 is also connected between the cathodes and grids of the tubes 212 and 213 and therefore these grids will rise in potential with the cathodes of the tubes 212 and 213. But current flowing through the tube 204 flows through the resistance 208 and produces a potential drop which causes the cathode of the tube 204 and the associated circuit including the gas tube 201 and the grids of the tube 204 to rise in potential in proportion to the current flowing in the tube 204 and in proportion to the current flowing in the tubes 212 and 213. It will thus be seen that the potential of each stage in the circuit rises and falls with the cathode of the succeeding stage, and this operates to produce amplification of the pulse formed by the network and at the same time causes the tubes to go on and off together. The choke 215 shunted across the resistance 214 acts similarly to the inductance 80 of Fig. 1 to discharge distributed capacities in the input of the load circuit and thus shorten the trailing edge of the pulse.

It will be seen from the description of Figs. 1, 2, and 3 that I have provided an efficient wide band amplifier which has particular value for use where high power amplification is desired, especially for the amplification of discrete pulses.

Many modifications of the invention may be made without departing from the spirit thereof, and I do not, therefore, desire to limit myself to what has been shown and described except as such limitations accrue in the appended claims.

What I desire to claim and secure by Letters Patent is:

1. An amplifier comprising a plurality of thermionic tubes connected together in cascade, each of said tubes having an input circuit and a cathode circuit including a resistor, the resistor in the cathode circuit of each tube being connected in the input circuit of the succeeding tube, and the cathode circuits of all tubes except the last tube being so connected to the cathode of the last tube that the potentials of these circuits can rise and fall with the potential of said last cathode.

2. An amplifier comprising a plurality of thermionic tubes connected in cascade, each of said tubes having at least a plate, a grid, and a

cathode, a separate cathode circuit including a resistor for each of said tubes, said resistors being in series, arranged in the order of the associated tubes, each of said resistors being connected between the grid and cathode of the next succeeding tube, a source of potentials, means to apply positive potentials from said source to the plates of said tubes, and means to apply a negative potential from said source to the cathode of the last of said thermionic tubes through the resistor in the cathode circuit thereof.

3. An amplifier comprising a thermionic tube having at least a plate, a grid, and a cathode, a cathode circuit for said tube, means associated with said cathode to raise the potential of said cathode with respect to a predetermined reference potential in proportion to the amount of current flowing through said cathode circuit, a condenser associated with the grid of said tube, means to charge said condenser, means to initiate the discharge of said condenser, means to cause the discharge of said condenser to apply a positive voltage pulse between said grid and cathode, means to control the discharge of said condenser so as to shape the voltage pulse thus applied to said grid in a predetermined manner, means to cause the potentials of said condenser, said discharging means, and said controlling means to follow the potential changes of said cathode, and an output circuit connected to said cathode to obtain voltage variations therefrom.

4. An amplifier comprising a thermionic tube having at least a plate, a grid, and a cathode, a cathode circuit for said tube, means connected to said cathode to raise the potential of said cathode with respect to a predetermined reference potential in proportion to the current flowing through said cathode circuit, a network including a condenser connected to said grid, means to charge said condenser to a predetermined potential, a gas tube connected across said network, means to cause said gas tube to become conductive so as to permit said condenser to discharge, whereby a positive potential with respect to said cathode will be applied to said grid, means to cause the potential of said gas tube, said network and said grid to follow the potential of said cathode, but to retain said positive potential of said grid with respect to said cathode, and an output circuit connected to said cathode to obtain voltage variations therefrom.

5. An amplifier comprising a thermionic tube having at least a plate, a grid, and a cathode, a cathode circuit for said tube, means associated with said cathode to raise the potential of said cathode with respect to a predetermined reference potential in proportion to the amount of current flowing through said cathode circuit, pulse forming means associated with said thermionic tube and including a pulse forming network, a gas tube, and a resistor connected to the cathode of said gas tube, said resistor being connected between the grid and cathode of said thermionic tube, means to charge said pulse forming network to a predetermined potential, means to cause said gas tube to become conductive so as to permit said pulse forming network to discharge whereby a positive pulse is applied between the grid and cathode of said thermionic tube, means to cause the potential of said gas tube, said pulse forming network and said grid to follow the potential of the cathode of said thermionic tube, but to retain said positive potential of said grid with respect to said cathode of said thermionic tube, and an output circuit

15

connected to the cathode of said thermionic tube to obtain voltage variations therefrom.

6. An amplifier comprising a thermionic tube having at least a plate, a grid, and a cathode, a cathode circuit for said tube, means associated with said cathode to raise the potential of said cathode with respect to a predetermined reference potential in proportion to the amount of current flowing through said cathode circuit, a condenser associated with the grid of said tube, means to charge said condenser, means to initiate the discharge of said condenser, whereby a positive voltage pulse is applied between said grid and cathode, means to cause the potentials of said condenser and said discharging means to follow the potential changes of said cathode, and

16

an output circuit connected to said cathode, to obtain voltage variations therefrom.
